UNITED STATES PATENT OFFICE.

GEORGE WILLIAM MOHR, OF JERSEY CITY, NEW JERSEY.

POR-T-HOLE VENTILATOR.

1,182,194.

Specification of Letters Patent.

Patented May 9, 1916.

Application filed February 4, 1916. Serial No. 76,108.

To all whom it may concern:

Be it known that I, GEORGE W. MOHR, a citizen of the United States, and a resident of Jersey City, in the county of Hudson and State of New Jersey, have invented certain new and useful Improvements in Port-Hole Ventilators, of which the following is a specification.

The object of this invention is to provide a means whereby the ports of ships or the like may be left open in rough or stormy weather, but without permitting the entrance of water, whereby ventilation may be had without the usual drawback. To this end a casing is provided at the inner side of the port, having a tight door giving access to its interior and transparent means in its walls to permit the free passage of light into the ship, this casing accommodating and permitting the movement of the usual or suitable port closures, and having automatic means, such as a float coöperating with a seat to permit the passage of air into the vessel while preventing the passage of water, when said door is closed. After passing such automatic means, the air current is preferably caused to flow through a circuitous course determined by baffles or the like, which further prevent the entrance of water into the vessel and which trap any moisture carried by the air before the latter emerges into the portion of the ship to be ventilated. A screen between the first chamber or box of the casing and the float chamber prevents the latter and the baffle passage becoming obstructed by seaweed and the like. These and other features of the invention will become apparent as the specification proceeds, reference being had to the accompanying drawings, wherein:

Figure 1 is a view of the device partly in front elevation and partly in vertical section; Fig. 2 is a vertical section taken in a plane at right angles to that of Fig. 1; Fig. 3 is a horizontal section on the line 3—3 of Fig. 2; and Fig. 4 is a view partly in front elevation and partly in vertical section of a modified construction.

The outer wall of the ship is represented at 1, 2 being a port and 3 the port frame. As is customary, the port may be closed by a hinged port-light 4 alone, or by the port-light in conjunction with an opaque shutter 5. These two elements may be of any ordinary or suitable construction, and are accordingly not illustrated in detail. The

light 4 is hinged at one side, as indicated at 6, and held hermetically closed by a clamp lock 8, of known construction. The hinge 7 of the opaque shutter is shown at the top, as is usual, but instead of a single clamp lock I prefer to provide this closure with two locks 8^a, located toward the sides and above the bottom, so that the bottom of the box, about to be described, may be brought as close as possible to the bottom of the port hole.

At the inner side of the port is secured a casing, of which the first chamber is formed by a box 9, this box being of suitable size and shape, but large enough, in any event, to accommodate the port closures 4 and 5 and to permit them to be swung open and closed. The walls of the box carry glass panes 10, and the front is adapted to be opened and closed by an inwardly opening hinged door 11, which also carries a pane of glass. This door affords access to the port closures and when open permits of direct ventilation. It is made tight against leakage of water in any suitable or approved manner, such as is adopted in conjunction with the port-lights themselves, and is clamped shut by a locking device 12. It will also be understood that the body of the box itself, the mounting of its panes of glass, and the joint where it is attached to the wall 1 are to be rendered water-tight by any of the known means and expedients adopted for such purposes.

On top of the box 9, in Figs. 1 and 2, there is a further inclosure 13, which affords a passageway for air from the interior of the box to the stateroom or other space in the ship to be ventilated, means being provided, however, whereby this passageway is closed or obstructed to water, so that the latter may not enter the ship. The interior of this inclosure is preferably separated from the box by a screen 14, which may be a perforated metal plate, or of any other construction sufficiently open to permit the free passage of air and sufficiently strong to withstand the pressure of the water. This screen performs the important function of keeping seaweed or other seaborn objects from entering the inclosure 13 and there interfering with the action of the devices about to be described.

When the iron shutter 5 is opened, it is supported beneath the screen 14 by a suitable catch indicated at 36, in which position it does not substantially obstruct the flow

of air into the inclosure 13. However, it is to be understood that I do not limit myself to hinging this closure at the top. In like manner, the light 4, which is shown hinged 5 exactly at the side, may be hinged elsewhere, if desired. As the parts are arranged, it will be understood that the light swings open adjacent one side wall of the box, while the door 11, when open, lies adjacent the opposite side wall. It will, of course, be understood without special illustration that catches may be provided for holding these members, also, in their open positions.

The lower part of the inclosure 13 comprises a float chamber 15, having an exit 16, of large area, through the partition 17. In this float chamber a float cage is formed by vertical members 18 which are removably secured in place by means such as indicated 20 at 19, for example. This chamber serves as a vertical guide and retainer for an automatic valve or float 20, which is preferably, though not necessarily, in the form of a ball, as shown, and which may be of hollow metal 25 or other appropriate material or construction. The ball illustrated rests upon the bottom of the float chamber, away from the exit 16, except when a rush of water passes through the screen 14, when it is raised so as 30 to close the said exit, thereby preventing the water going beyond the float chamber.

The exit 16 preferably comprises a tube having its lower end flared, as shown at 21, and internally threaded for the reception of 35 a hollow screw-plug 22 having a lip 33 which clamps a rubber gasket or valve seat ring 23 against the said flared end. The opening 34 through said plug is of polygonal form, so that the plug may be inserted and removed with the aid of a suitable wrench.

On top of the exit tube 16, above the partition 17, is a cap 24, which serves to throw back any spray which may dash upward through the exit before the float closes the 45 opening. The air passes out laterally beneath this cap, through openings 25, and thus into the upper chamber 26 of the inclosure 13. This chamber is constituted as a staggered or circuitous passage by the provision therein of a suitable number of baffles 50 27 inclining downward in reverse directions from the opposite side walls. The top or outlet of the inclosure is preferably screened, as shown at 28, to prevent objects being 55 dropped therein, and may be opened and closed by a solid top 29, hinged at 30, and provided with suitable adjusting means, indicated at 31, such as are employed for opening and closing transoms and the like.

60 A suitable door 35 affords access to the interior of the inclosure 13, and to the parts therein contained.

From the foregoing it will be understood that under weather conditions which would 65 otherwise require the port to be closed, the

usual closures 4 and 5 may be both opened, and, the door 11 being closed, no water will find its way into the ship, the air, however, being free to pass through the box 9 and inclosure 13 and thence into the ship. Any 70 body of water which gains admission to the chamber 15 beyond the screen 14 is prevented from passing farther by the float 20, which automatically closes the opening 16, and when the rush subsides the water drains 75 back into the tight box below, and thence out through the port-hole. In addition a drain may be provided, as indicated at 32, leading to a suitable point of discharge. Spray is thrown back by the cap 24 as described, and 80 any water which may succeed in passing through the exit from the float chamber is prevented by the baffles from escaping from the outlet of the inclosure into the ship. These baffles also relieve the air current of 85 any free moisture which it carries. It will be understood, of course, that these devices will act also to keep out snow. In fair weather the door 11 is opened, as well as the port closures 4 and 5, the ventilation then 90 being direct from the port through the box to the interior of the ship.

The construction shown in Fig. 4 is similar to that just described, except that the inclosures 13^a containing the float and float chamber and baffles is at one side of instead of above the box 9^a, as may be preferable in certain cases. With this construction I prefer to provide the box with a lateral extension 9^b, also having transparent walls, so that 95 adequate lighting is insured. The screen 14^a, instead of being placed horizontally at the top of the box, as in Figs. 1 and 2, is disposed vertically between the interiors of the chamber 15^a and the box extension 9^b. Just 100 inside this screen a deflector 36 extends 105 downward and inward from the upper side portion of the chamber, in order to direct in-rushing water to the bottom of the float chamber, thereby insuring the operation of the float. Otherwise the construction is substantially that already described.

In conclusion I wish it to be understood that I do not limit myself to the form, proportions or the specific devices illustrated, and that numerous changes may be made and equivalents substituted without departing from the essentials of the invention. For example, while I now deem it preferable to employ a float valve of the character illustrated, I do not necessarily limit myself thereto, since other devices may be used for performing the same functions in substantially the same way. It will be obvious also that the invention may be used in light-houses and in other locations where conditions are similar to those on board ship.

What I claim as new is:

1. The combination with a port of a ship or the like, of a box at the inner side of the 130

port having transparent means in its walls and a door, and a chamber separated by a screen from the interior of said box, said chamber having an exit for air and means for closing said exit to the egress of water.

5 2. The combination with a port of a ship or the like, of a box at the inner side of the port having transparent means in its walls and a door, a chamber separated by a screen from the interior of said box, said chamber having an exit for air and means for closing said exit to the egress of water, and means affording a circuitous passageway for the air after leaving said exit and before emerging into the space to be ventilated.

10 3. The combination with a port of a ship or the like, of a box at the inner side of the port having transparent means in its walls and a door, a chamber separated by a screen from the interior of said box, said chamber having an exit for air and means for closing said exit to the egress of water, and a second chamber communicating with the exit of the first and itself provided with an outlet for the air, the said second chamber containing staggered baffles in the path of the air.

15 4. The combination with a port of a ship or the like, of a box at the inner side of the port having transparent means in its walls and a door, a chamber separated by a screen from the interior of said box, said chamber having an exit for air and means for closing said exit to the egress of water, a cap over the exit from said chamber, and means affording a circuitous passageway for the air flowing out from beneath said cap, the said means having a screened outlet into the space to be ventilated.

20 5. The combination with a port of a ship or the like having hinged closures, of a box at the inner side of the port inclosing said hinged closures and permitting the movement thereof, said box having transparent means in its walls and a door, an inclosure communicating with the interior of the box, a suitable screen interposed between the interiors of the box and inclosure, the said inclosure having an inlet chamber provided with an exit, a member in said inlet chamber for preventing the passage of water through said exit, walls within the portion of the inclosure into which said exit opens for relieving the air current of carried moisture, an outlet from the said portion of the inclosure to the space to be ventilated, and a closure for said outlet.

25 6. The combination with a port of a ship or the like, of a box at the inner side of the port having transparent means in its walls and a door, a chamber communicating with the interior of the box and having an exit, a suitable screen interposed between the interiors of the box and chamber, and a float in said chamber adapted to permit the egress

of air therefrom but to retain water which may gain entrance to the chamber from the box.

7. The combination with a port of a ship or the like, of a box at the inner side of the port having transparent means in its walls and a door, a chamber communicating with the interior of the box and having an exit, a suitable screen interposed between the interiors of the box and chamber, and a float in said chamber adapted to permit the egress of air therefrom but to retain water which may gain entrance to the chamber from the box, the said float being in the form of a ball.

8. The combination with a port of a ship or the like, of a box at the inner side of the port having transparent means in its walls and a door, a chamber communicating with the interior of the box and having an exit, a suitable screen interposed between the interiors of the box and chamber, a cage in said chamber, and a member guided in said cage to close said exit to the passage of water but not of air.

9. The combination with a port of a ship or the like, of a box at the inner side of the port having transparent means in its walls and a door, an inclosure at one side of said box, a screen between the interiors of the box and inclosure, and means in said inclosure for permitting the passage of air and preventing the entrance of water into the ship.

10. The combination with a port of a ship or the like, of a box at the inner side of the port having a lateral extension, transparent means in the walls of the box and its extension, a chamber beside said extension and separated therefrom by a suitable screen, a float in said chamber adapted to permit the passage of air but to prevent the escape of water from the chamber into the ship, and means whereby water entering the box and thence passing through the screen into the float chamber is directed to the bottom of the latter.

11. The combination with a port and port-closing means of a ship or the like, of a casing at the inner side of the port, accommodating the port-closing means and itself provided with a door, which when open permits of direct ventilation and affords access to the port-closing means, transparent means in the walls of the casing affording passage for the light from the port to the interior to be ventilated, and means for permitting air to pass from the casing to the said interior while preventing the entrance of water thereto when the said door is closed.

12. The combination with a port and port-closing means of a ship or the like, of a box with transparent walls at the inner side of the port, accommodating the port-closing

- means and itself provided with a door, which when open permits of direct ventilation and affords access to the port-closing means, means affording a passageway for air from said box to the interior of the ship, and means comprising an automatically operating device supplemented by baffles for preventing the escape of water through said passageway into the vessel.
- 10 13. The combination with a port and port-closing means of a ship or the like, of a box with transparent walls at the inner side of the port, accommodating the port-closing means and itself provided with a door, which when open permits of direct ventilation and affords access to the port-closing means, means affording a passageway for air from said box to the interior of the ship,
- 15

and means comprising a normally open valve coöperating with a seat for closing 20 said passageway to the passage of water.

14. The combination with a port of a ship or the like, a port-light, and an opaque shutter, the latter hinged at the top and having two locking devices toward opposite sides 25 and above the bottom, of a box secured at the inner side of the port and accommodating the port-light and shutter, transparent means in the wall of the box, a door affording access to the port closures and permitting of direct ventilation, and means affording a passageway for air but not for water from the box to the space to be ventilated when said door is closed.

GEORGE WILLIAM MOHR.
